UNITED STATES PATENT OFFICE.

GLENVILLE A. COLLINS, OF LOS ANGELES, CALIFORNIA, ASSIGNOR TO SOUTHWESTERN ENGINEERING CORPORATION, OF LOS ANGELES, CALIFORNIA, A CORPORATION OF DELAWARE.

BOILER CONSTRUCTION.

Application filed July 21, 1924. Serial No. 727,196.

This invention relates to boilers.

The general object of the invention is to provide an improved boiler of the water tube type.

5 One of the specific objects of the invention is to provide a water tube boiler, including curved tubes and a transverse drum, with a water leg.

A further object of the invention is to 10 provide a boiler, including water tubes and steam and water drums, with means whereby steam entering the water leg can be taken off in the drums thereby permitting the circulation to continue around the circuit of the 15 boiler.

An additional object of the invention is to provide a boiler including a pair of disengaging drums together with means whereby steam may be taken from one drum, 20 superheated and conducted to the other disengaging drum where the superheated steam mixes with the saturated steam, thus causing an equalizing of temperatures and affording a steam carrying a desired degree of super- 25 heat.

An additional object of the invention is to provide a water tube boiler with a water leg which is preferably rectangular, together with a connecting member of novel 30 form for connecting the water leg with a cylindrical drum.

A further object of the invention is to provide a water tube boiler with a water leg which is secured to and which aids in supporting the tubes constituting the main circulatory members of the boiler.

Another object of the invention is to provide a water tube boiler having a water leg with means for holding and supporting circulation tubes so that the water and steam in the bottom bank of tubes may have unimpeded circulation and wherein the water leg is connected with a steam and water drum so that steam entering the water leg 45 may be transferred to the adjoining drum and there disengaged.

A further object of the invention is to provide a water tube boiler with a water leg which is connected to a drum or cross drum and wherein the communicating passageways between the water leg and the cross drum is defined by slots or holes in the drum thereby freely admitting water and steam and tending to produce disengaged steam bubbles 50 of more uniform size.

A further object of the invention is to provide a steam boiler of the water tube type including a water leg wherein the water leg is connected to the cross drum with a connecting member wherein the communicating area is composed of a plurality of sections disconnected to provide intervening metal whereby the strength of the drum is unimpaired by the passageway.

Another object of the invention is to provide a water tube boiler including a water leg with a baffle plate supported over the water leg connection.

An additional object of the invention is to provide a water tube boiler including circulation tubes and drums with a bubble plate arranged under the steam outlet to provide a more uniform steam product.

Other objects of the invention will be apparent from the following description taken in connection with the accompanying drawings, wherein:

Figure 1 is a section, partly in elevation, showing my improved boiler;

Fig. 2 is a front elevation, partly in section, showing the boiler;

Fig. 3 is a fragmentary perspective view of the member for connecting the water leg with the forward cross drum;

Fig. 4 is a fragmentary bottom plan view 85 of the forward drum showing the connecting member;

Fig. 5 is a detailed elevation; and

Fig. 6 is a fragmentary perspective view of the baffle.

Referring to the drawing by reference characters I have shown a boiler embodying the features of my invention at 10. This boiler comprises a boiler setting 11 having a space 12 for a furnace therein and having a breeching 14 to the smoke stack.

The boiler shown is of the water tube type and includes a mud drum 15. A pair of steam and water drums 16 and 17 are located above the mud drum. The drums 15 and 16 are shown as connected by banks of tubes 18. A water leg which is preferably a rectangular metal member is shown at 19 as having parallel front and back portions. The drums 15 and 16 are connected to the water leg 19 by banks of curved tubes 20 and 21 respectively.

The steam and water drum 16 is indicated as provided with a feed water pipe 22 and with a steam discharge pipe 23. The drum 110

17 is shown as provided with the usual water gauge 25.

The boiler may be provided with baffles 23 which may be arranged in a manner to conduct the hot gases properly. It will be understood that the boiler is adapted for use with various types of heat reducing devices whether it is coal, oil or gas. The arrangement of baffles also may be changed to suit various conditions.

The water leg 19 is shown as arranged at the ends of the banks of curved tubes 20 and 21. These tubes are arranged in the rear wall 30 of the water leg and in order to afford ready access for cleaning and repair of these tubes I show the front wall 31 opposite the rear wall 30 as provided with a plurality of key caps 32. These key caps may be removed when desired allowing ready access to the tubes 20 and 21.

In order to connect the water leg 19 with the drum 17 I provide a metallic throat piece 35 which may be constructed as a single piece member, or if desired it may be made of a plurality of parts.

This connecting member is provided with a rectangular bottom portion 36 which may be secured to the water leg 19, by rivets such as shown at 37. The rivets are shown as single, although they may be double and staggered, if desired. The upper portion of the connecting member 36 is shown as curved as at 38 to fit the under portion of the drum 17.

35 The water leg is placed in communication with the drum 17 by means of a plurality of apertures 40 in the lower part thereof. These apertures are shown as a plurality of spaced holes in the lower portion of the drum. The spacing of the holes leaves strips of metal therebetween thus greatly preserving the strength of the drum and at the same time in the aggregate furnishing a passageway of large area through which the water passes thus tending to prevent surging.

40 The drum 17 is shown as provided with a baffle 45 which is provided with apertures along the bottom edge thereof to allow passage of water. The baffle 45 extends over the openings 40 thus aiding in preventing surging of the water.

45 The drums 16 and 17 are shown as connected by tubes 50 which are arranged adjacent the upper portion 51 of the boiler setting. The tubes 50 provide, in effect, a superheater so that the steam which is disengaged in the drum 17 and which passes through the tubes 50 is superheated during passage. The superheated steam, upon leaving the tubes 50, mingles with the saturated steam in the drum 16 thus lowering the temperature of the superheated steam entering drum 16 and providing a steam product having a desired degree of superheat.

50 In using my improved boiler it will be

apparent that a circulation is maintained through the banks of tubes 18, 20 and 21. The steam which forms in the water leg 19 rises into the drum 17 and is disengaged in the upper steam space of this drum whence it passes to the drum 16 through the superheater 50. After the water passes through the tubes 21 other steam is disengaged in the drum 16 and this mingles with the steam disengaged in 17 and which has passed through the superheater 50, as explained.

The banks of tubes are preferably arranged in rows with alternate wide and narrow spaces between the rows, as shown in the drawing.

55 It will thus be seen that I provide a main water circuit through the drums 15 and 16 and the water leg 19 and steam is disengaged in the drum 17 independently of the circuit mentioned.

What I claim is:

1. In a boiler, a plurality of drums, including a mud drum, a steam and water drum, a bank of tubes connecting said steam and water drum and the mud drum, a water leg, a bank of tubes connecting the water leg to the mud drum and a third bank of tubes communicating directly with the water leg and with the steam and water drum to provide a water circuit, said mud drum being below said steam and water drum, a third drum, said third drum being located above the water leg, and means providing a passageway having a cross sectional area but slightly less than the interior cross sectional area of the water leg for connecting the water leg to the third drum whereby the velocity of water ascending in the water leg is low.

100 2. In a boiler, a plurality of drums, including a front drum, a rear mud drum and a rear steam and water drum, a bank of tubes connecting said steam and water drum and the mud drum, a water leg, said water leg directly communicating with said front drum, a second bank of high-angle curved tubes connecting the rear face of the water leg to the mud drum, a third bank of tubes directly connected to the steam and water drum, all of said third bank of tubes being directly connected to the water leg to provide a water circuit.

105 3. In a boiler, a mud drum, a steam and water drum, tubes connecting said drums, a water leg, a bank of tubes connecting said water leg with each of said drums to provide a water circuit wherein the water moves freely, a third drum, said third drum having an aperture therein, means disposed around said aperture and connecting the water leg with the third drum whereby disengaged steam may be delivered in the third drum and other tubes connecting the third drum and the first mentioned steam drum, said other tubes being adapted to superheat

steam disengaged in the third drum and direct such superheated steam to the second drum where it will mingle with the saturated steam disengaged in the second 5 drum to produce steam with a low degree of superheat, the steam disengaged in said water circuit and the steam passing through said other tubes moving in the same direction and producing dry steam moderately superheated and with but slight geysering action 10 whereby a steady water level is maintained.

4. In a boiler, a plurality of drums, including a front drum, a rear mud drum and a rear steam and water drum, a bank of 15 tubes connecting said steam and water drum and the mud drum, a water leg, said leg

having parallel front and back faces, a bank of curved tubes connecting the rear face of the water leg to the mud drum, a bank of tubes connecting the rear face of the water leg to the steam and water drum to provide a water circuit, means connecting said front drum directly with the water leg, means spaced entirely above said third mentioned bank of tubes connecting the front drum to 20 the rear steam and water drum, said rear steam and water drum having a steam outlet therein.

In testimony whereof, I hereunto affix my signature.

GLENVILLE A. COLLINS.
